Letter Patent No. 2379. Dated Aug. 7. 1866.

Antidated July 10. 1866.

Design for the plate of a stone

The Schedule referred to in the Letter Patent and making part of the same

To all whom it may concern:

Do it knowe that we, G. Smith and H. Brown of Philadelphia, County of Philadelphia, State of Pennsylvania, have invented or produced a new and original Design for the Plate of the "Violet" Stove; and we do hereby declare the accompanying drawing with the following explanation of the same to form a full, clear and exact description of the said Design.

In the accompanying drawing,

Fig. 1, represents the top plate of the "Violet" Stove

Fig. 2, the upper base plate, and

Fig. 3, the lower base plate.

The top plate A, is of the form shown in the drawing and at the edge of the same is a plain moulding a, and an inner ornament a'.

In the centre of the plate is an annular projection c, which encloses an annular register b, and within the latter is an opening y.

At each side of the register and also at the rear of the same is an ornamental figure d, and on the face of the plate between the said figures, and round the rib c, are foliated ornaments of the form shown in the drawing.

The upper base plate B, is bordered by an ornamental edging e, and around a circular opening y', in the centre of the plate are a series of radial projections forming an ornamental border i.

At each side of the opening y', and at the rear of the same is an oblong opening y, each of which is enclosed by an ornamental border i.

At each side of the opening y, and at the rear of the same is an oblong opening g, each of which is enclosed by an ornamental border i.

The lower base-plate C, is bordered by an ornamental edging m, and on the face of the same near the front edge is the word "Violet".

We claim,
the design for the plates of the "Violet" Stove substantially as shown in, and by the accompanying drawings
on testimony whereof we have signed our names to this specification in the presence
of two subscribing witnesses, —
